(57) **CLAIM**

The ornamental design for a “deck light”, as shown and described.

DESCRIPTION

FIG. 1 is a top rear right perspective view of the “deck light” design according to the present invention;

FIG. 2 is a bottom front right perspective view of the “deck light” shown in FIG. 1;

FIG. 3 is a rear elevational view of the “deck light” shown in FIG. 1;

FIG. 4 is a front elevational view of the “deck light” shown in FIG. 1;

FIG. 5 is a right side elevational view of the “deck light” shown in FIG. 1;

FIG. 6 is a left side elevational view of the “deck light” shown in FIG. 1;

FIG. 7 is a bottom plan view of the “deck light” shown in FIG. 1; and,

FIG. 8 is a top plan view of the “deck light” shown in FIG. 1.

Portions of the “deck light” are shown in phantom lines and form no part of the design.

1 Claim, 3 Drawing Sheets
